UNITED STATES PATENT OFFICE.

ABBOT AUGUSTUS LOW, OF HORSESHOE, NEW YORK.

CUTTING IMPLEMENT.

No. 875,939.

Specification of Letters Patent.

Patented Jan. 7, 1908.

Application filed April 25, 1907. Serial No. 370,149.

To all whom it may concern:

Be it known that I, ABBOT AUGUSTUS Low, a citizen of the United States, residing at Horseshoe, St. Lawrence county, and 5 State of New York, have invented certain new and useful Improvements in Cutting Implements, of which the following is a specification.

My invention relates to cutting implements designed to be carried upon the person ready for use in emergency for the purpose of severing flower stems, cord, and other things relatively small in cross section,—the object being to afford an implement which may be safely carried in the pocket or manipulated without danger or inconvenience to the user.

The invention consists essentially in the combination with a rigid cutting blade and 20 handle of a pivoted cutting edge guard formed with a groove opposed to the cutting edge the parallel edges of said grooved guard being adapted to act as bearings to force the object to be severed against the 25 cutting edge, as hereinafter described and claimed specifically.

In the accompanying drawings, Figure 1, is a front or top view of my improved implement Fig. 2, a side elevation thereof; Fig. 3, 30 is a horizontal section upon plane of line 3—3—Fig. 1; Fig. 4, an end elevation; Fig. 5, a transverse section upon plane of line 5—5—Fig. 2.

The main portion of the implement consists 35 of the body A, formed with the cutting blade a, and shank a'. The shank a', is formed with a recess a², between the side walls of which is fulcrumed the tongue b, of the combined guard and anvil B, which latter 40 extends the whole length of the cutting blade a and shank a', so that the forward end b', protects the cutting edge a³, while the rear extremity b², extends over the shank a' and is held normally thereon by a spring s, 45 said spring s fitting in the recesses a⁴, and b⁴, formed for its reception in the opposed sides of the shank a', and the rear extension of the guard B, and having its ends attached to 50 said parts so that its action is retractile in character.

The inner side of the guard B opposed to the cutting edge a³, is formed with a longitudinal groove b². The parallel edges b²², b²², of this longitudinal groove b², act as bearing 55 surfaces for the article to be severed,—and as these parallel bearing surfaces are upon op-

posite sides of the cutting edge a³, they support the article against said cutting edge, so as to effect the severance of the article in true cross section or at right angles to its longitudinal axis. 60

The forward end b', of the guard is broadened and rendered slightly concave as shown in Figs. 1 and 4 to form a thumb rest or bearing by which the guard may be safely 65 and conveniently forced toward the cutting edge against the resistance of the article to be severed.

My implement is especially adapted for use in pruning and for like purposes since it 70 affords ample protection to the thumb and fingers of the user.

What I claim as my invention and desire to secure by Letters Patent is,

1. In an implement of the character designated, the combination of a straight cutting blade formed with a straight shank in alignment with said blade and integral therewith, a guard pivoted to the shank adjacent to the inner end of the cutting blade and formed 75 with a rear extension coinciding with the shank of the cutting blade and resting thereon when in its normal position, and a retractile spring situated in coinciding recesses in the opposed inner side of the shank and 80 guard extension and having its opposite ends respectively attached to said opposed parts, for the purpose described.

2. In an implement of the character designated, the combination of a straight cutting 90 blade formed with a straight shank in alignment with said blade and integral therewith, a guard pivoted to the shank adjacent to the inner end of the cutting blade and formed with a rear extension coinciding with the 95 shank of the cutting blade and resting thereon when in its normal position, a retractile spring situated in coinciding recesses in the opposed inner sides of the shank and guard extension and having its opposite ends re- 100 spectively attached to said opposed parts, the forward portion of the guard being so shaped that when in its said normal position there is a space between its inner side and the cutting edge for the reception of articles to be 105 cut, substantially as and for the purpose described.

3. In an implement of the character designated, the combination of a straight cutting blade formed with a straight shank in alignment with said blade and integral therewith, a guard pivoted to the shank adjacent to the 110

inner end of the cutting blade and formed with a rear extension coinciding with the shank of the cutting blade and resting thereon when in its normal position, a retractile spring situated in coinciding recesses in the opposed inner sides of the shank and guard extension and having its opposite ends respectively attached to said opposed parts, the forward portion of the guard being so shaped that when in its said normal position there is a space between its inner side and the

cutting edge for the reception of articles to be cut, said guard being also formed with a longitudinal groove on its inner side and with a relatively broad concave thumb rest upon its upper or outer side for the purpose described. 15

ABBOT AUGUSTUS LOW.
